BY William J. Jackson
ATTORNEY.

UNITED STATES PATENT OFFICE.

FRANCES L. STREITFIELD, OF ATLANTIC CITY, NEW JERSEY.

METHOD OF SECURING ATTACHING STRINGS TO WEARING APPAREL.

1,405,171.

Specification of Letters Patent. Patented Jan. 31, 1922.

Application filed March 17, 1921. Serial No. 452,943.

To all whom it may concern:

Be it known that I, FRANCES L. STREITFIELD, a citizen of the United States, residing at Atlantic City, county of Atlantic, 5 and State of New Jersey, have invented a certain new and useful Method of Securing Attaching Strings to Wearing Apparel, of which the following is a specification.

The leading object of the present invention is to eliminate the sewing of attaching strings to articles of wearing apparel such as babies' caps or bonnets, sun-bonnets, night gowns, corset covers, pajamas and the like and provide a simple, inexpensive and 15 practical method of applying the same.

The invention consists of the improvements hereinafter described and finally claimed.

The nature, characteristic features and 20 scope of the invention will be more fully understood from the following description taken in connection with the accompanying drawings forming part hereof, and in which:

Fig. 1, is a fragmentary view of an article of wearing apparel illustrating a string or strap ready for application thereto.

Fig. 2, is a similar view illustrating the first position of a string or strap as applied thereto.

Fig. 3, is a similar view illustrating the second position of a string or strap as applied thereto.

Figs. 4 and 5, are similar views illustrating the third and last positions of a string or strap as applied thereto, and

Fig. 6, is a perspective view of a baby's cap or bonnet having applied thereto attaching strings or straps in accordance with 40 the present method.

For the purpose of illustrating my invention, I have shown in the accompanying drawing one form thereof which is at present preferred by me, since the same has 45 been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, 10 designates an article of wearing apparel which may be a baby's 50 cap or bonnet, a night-gown, a corset-cover, pajamas or other garment in which opposed

parts are to be secured together by strings or straps. 11 designates an attaching string or strap adapted to be secured to article 10. According to my present method, instead of 60 sewing the string or strap 11 to article 10, I removably secure the parts together and in this connection, it is to be noted that no pins, clamps, brads or like fastening mediums are employed. In practicing the 65 present method, I first form in each part of article 10 to which a string or strap 11 is to be attached a buttonhole 12, see Fig. 1. I then form in end A of a string or strap 11 a pair of spaced button-holes 70 13—14 see Fig. 1. End B of a string or strap 11 is then passed first to the rear of and then outwardly through button-hole 12 in article 10 as shown in Fig. 2. End A of a string or strap 11 is next folded outwardly over upon itself so that button-hole 75 14 overlies and registers with button-hole 13, see Fig. 3. The end B of a string or strap 11 is then passed through aligned button-holes 14—14 to the rear of part A as 80 clearly shown in Fig. 4. The parts are now drawn taut thereby securely attaching a string or strap to article 10. When drawing the parts taut the part A being in the form of a loop provides a bow-effect as clearly 85 shown in Fig. 5. As shown in Fig. 1, of the drawings, the part A is enlarged or widened out as at C—C in order to enhance the bow-effect although this is not always necessary. Strings or straps so applied 90 form an efficient, practical, neat and inexpensive method of attachment and while readily removable cannot become accidentally detached as is frequently the case when sewed to place. Further, no metallic parts 95 are provided in the present means of attachment. It sometimes happens that an article itself does not require washing or is made of such fine material as to preclude washing thereof, yet it is desirable to wash 100 the attaching strings or straps which become unduly soiled because of frequent handling. According to the present invention, the attaching strings or straps may be readily removed for washing purposes and 105 quickly attached without sewing. Another advantage results to travelers in that it is not necessary to be provided with sewing equipment in order to replace an attaching string or strap in accordance with the present method.

It will now be apparent that I have de-

vised a novel and useful construction which embodies the features of advantage enumerated as desirable in the statement of the invention and the above description and 5 while I have in the present instance shown and described the preferred embodiment thereof which has been found in practice to give satisfactory and reliable results, it is to be understood that the same is susceptible of modification in various particulars without departing from the spirit or scope 10 of the invention or sacrificing any of its advantages.

What I claim is:

15 1. The herein described method of securing an attaching string or strap to an article of wearing apparel which consists in forming a button-hole in said article, passing through said button-hole one end of a 20 string or strap, the opposite end of which is provided with spaced buttonholes, folding said string or strap so that the button-holes thereof are in alignment and passing that

end of said string or strap which has been passed through the first mentioned button-hole through the last mentioned button-holes and then drawing taut the interengaged parts. 25

2. An article of manufacture formed of textile fabric having a button-hole therein, 30 a string or strap of textile structure one end of which is provided with button-holes disposed in register the opposite end of said string or strap passing first through the article buttonhole and then through the last 35 mentioned button-holes said string or strap being drawn taut to securely interengage said parts.

3. A construction as described in claim 2, characterized by said string or strap having an enlarged portion adjacent its buttonholes which portion provides a bow-effect when the parts are drawn taut. 40

In testimony whereof, I have hereunto signed my name.

FRANCES L. STREITFELD.
